UNITED STATES PATENT OFFICE.

HERMAN B. KIPPER, OF MUSKEGON, MICHIGAN.

ALKALI-METAL CYANIDE PRODUCTION.

Application filed March 1, 1926. Serial No. 91,590.

- This invention relates to novel apparatus for the production of cyanide or similar compounds. It is well known and understood that if nitrogen or air which contains nitrogen is passed over sodium carbonate, or analogous carbonates, carbon and iron mixed together, at a high temperature above 900 to 1000 degrees centigrade, the nitrogen will combine with the carbon and the element of sodium so as to produce sodium cyanide. And the same underlying principle of chemical action may be utilized to produce other cyanides or analogous compounds such as potassium cyanide and the like.
- While knowledge of these reactions has been known for a great many years the commercial production of such cyanide compounds has only recently been attained. Many forms of apparatus have been tried and attempted for this purpose and I have secured a Patent 1,322,026, granted November 18, 1919, on an apparatus which, while a marked improvement over prior apparatus for the same purpose, is not sufficiently perfected and complete for the commercial production of the desired cyanides. After extensive experiments and trials I have produced the apparatus shown in the accompanying drawing and described in the following description with which commercial quantity production and a very rapid production of the cyanide desired may be had. In these drawings, Fig. 1 is a longitudinal vertical section through a part of said apparatus.
- Fig. 2 is a transverse vertical section through the receptacle or container in which the reactive ingredients used for the production of the cyanide are received.
- Fig. 3 is a plan view of the complete apparatus, and
- Fig. 4 is a fragmentary vertical section through one element of the apparatus which is used for the production of carbon monoxide.
- Like reference characters refer to like parts in the several figures of the drawing.
- In the construction of the apparatus which I have provided, a relatively large cylinder 1 is used, shown as positioned horizontally, at the upper side of which is an inlet pipe 2 normally closed by a cover 2^a and having mounted below its upper end a door 3 which, in the position shown in Fig. 1, is located across the pipe 2 and serves as a bottom member of a hopper supporting the materials which are to be introduced into the cylinder when the
- same are put in the pipe 2, cover 2^a being removed. Then after cover 2^a is replaced the door 3 may be turned so as to dump the materials into the cylindrical container 1. The outlet to this container is adjacent one end and at the lower side, as indicated at 4, the solid products passing from the cylinder through this pipe into a chamber 5 from which they are conveyed outwardly by a screw conveyer 6 or other equivalent means. A pipe 5^a leads into the chamber 5 through which nitrogen is forced into said chamber to obviate decomposition of the cyanide compounds which are received in the chamber 5 at a high temperature and which at such very high temperature rapidly decompose in the presence of oxygen or carbon dioxide.
- The ends of the cylindrical container 1 are closed by end plates 7. A sleeve 8 passes through each of the end plates 7 and is rotatably mounted therein, each at its inner end having a member 9 secured thereto between which a plurality of beveled scraper bars 10 are located being secured at their ends to the members 9 and reinforced and strengthened between their ends by rings 11, shown. A shaft 12 passes through and is rotatably mounted in the sleeves 8 and has bearings at its ends at the upper ends of posts 13 and 13^a, as shown in Fig. 1. A number of spiders 14 having radiating arms are fixed at spaced apart distances to the shaft 12 and a second series of beveled bars 15 are attached to and extend between the arms of said spiders. Shaft 12 is driven by means of a pulley 16 attached to the shaft between the posts 13 and 13^a at one end of the cylindrical container, a belt 17, from any suitable source of power passing around the pulley 16. It is designed that the shaft 12 shall be rotated at comparatively high speed or substantially 300 R. P. M. The sleeves 8 are driven from a shaft 18 suitably mounted at one side of the apparatus and having sprocket wheels 19 located in the same vertical planes with the other larger sprocket wheels 20 attached to the outer ends of said sleeves 8, sprocket chains 20^a passing around the wheels. The shaft 18 may be driven in any suitable manner at low speed so that the sleeves 8 turn very slowly, usually not more than 1 R. P. M.
- Two pipes 21 and 22 are connected with the cylinder 1 adjacent its opposite ends. The pipe 21 leads from said cylinder to a scrubber 23 which may be of any well known and conventional construction similar to the scrub-

bers used in purifying and washing gases, as in the production of illuminating gas. The specific details of construction of the scrubber need not be entered into. As will later appear, carbon monoxide gas passes from the cylinder 1 through the pipe 21 to the scrubber and these gases are freed therein from any cyanide or other dust, the carbon monoxide gas passing from the scrubber through a pipe 24 to the air preheater system in which the burning of the carbon monoxide is utilized for the preheating of air.

The pipe 24 is connected with two pipes 25 and 26 which extend oppositely to each other, one leading to a stove 27 and the other to a similar stove 28. At the junction of the pipes 24, 25 and 26, a control damper 29 is positioned which may be moved to two different positions, in one of which the gases passing through the pipe 24 may be led to the stove 27 and in the other of which said gases may be led to the stove 28. Three blowers 30, 31 and 32 driven by small electric motors are associated with the pipes 24, 25 and 26, as shown in Fig. 3, for blowing air into said pipes. The stoves 27 and 28 have outlet pipes 33 and 34 which come together and are joined and at their junctions are equipped with a second damper 35, which turned to different positions, directs the products of combustion from a stove which is burning the carbon monoxide gas to the stack 36 and directs the air which is heated by passing through the other stove so as to pass through an outlet pipe 37 to a gas producer 38, shown in Fig. 4.

It is to be understood that the stove 28, shown in Fig. 3, has previously been heated to a very high degree of temperature and that the air forced therethrough by the blower 32 in passing through said stove is raised to a high degree of temperature. The stove 27 in the meantime is being heated to a high-degree of temperature by the burning carbon monoxide gas. When stove 27 has reached its proper temperature and stove 28 has become cooled, the positions of the dampers 29 and 35 are changed so that air is blown through the stove 27 and heated therein as it passes to the gas producer 38 and the stove 28 is reheated by burning carbon monoxide therein.

The preheated air which passes through the pipe 37 to the gas producer 38 serves to combine with carbon located within the gas producer 38 and which is introduced therein through an upper inlet neck 39, in which a gate 41 is movably mounted and which may be operated to drop coke or other similar carbon material into the gas producer 38, this gate closing the inlet 39 when in the position shown in Fig. 4. The coke or other carbon 41 is shown at the lower end of the gas producer and the pipe 37 carrying the preheated air thereinto enters at the bottom of said gas

producer. Carbon monoxide mixed with nitrogen is produced and by reason of the high degree of temperature to which the air has been preheated the carbon monoxide and nitrogen which passes through the pipe 22 to the cylinder 1 are at a very high degree of temperature, usually between 1000 and 1800 degrees centigrade.

The operation of this apparatus may be described as follows:

The reaction material in finally divided state, such as sodium carbonate, carbon and iron, having been introduced into the cylinder 1 through the inlet pipe 2 and with the shaft 12 and connected bars 15 rotating at approximately 300 R. P. M. is continually stirred and agitated and is beaten and ground and maintained in its finally divided condition and stirred and kept disseminated by reason of the mechanical beating, grinding, stirring and lifting to which it is subjected by the rapidly rotating bars 15. Carbon monoxide and nitrogen from the air which has been used in burning the fuel in the gas producer, passing through the pipe 22 to the cylinder and at a temperature between 1000 and 1800 degrees centigrade, is brought into very intimate relation with the reacting material and there is produced by the reaction, sodium cyanide and additional carbon monoxide, the sodium carbonate releasing its atoms of oxygen and combining with nitrogen to make the cyanide, while the oxygen released combines with the carbon of the reacting material to make carbon monoxide. The cyanide produced falls into the receiving chamber 5 filled with nitrogen, and is there cooled, being removed by the conveyer 6 after it has properly cooled, while the carbon monoxide produced is carried through the pipe 21 to the scrubber 23 and is then burned to heat the stoves 27 and 28, as previously described.

The reactions which take place in the container 1 do not produce heat but on the contrary require the presence of a large quantity of heat which is absorbed during the progress of the reactions. It is for this reason that the air which passes through the gas producer 38 is reheated to very high degree of temperature so that all heat possible which can be provided and carried into the cylinder 1 is obtained, advantage being taken of the fact that the large production of carbon monoxide during the reactions forms a fuel which may be burned to provide for preheating the air as described.

The continuous grinding, beating and dissemination of the reactive materials within the cylinder maintains the same in a more or less pulverized condition so that the highly heated carbon monoxide is brought into intimate relation with all of the particles of the reactive mixture causing the reactions to take place very rapidly. The movement of the scraper bars 10 keeps the inner sides of the container free of any ma-

terials which may tend to cake and build up thereon and also serves to help maintain the reactive material in broken condition and so that the same may be better acted upon by the

5 beating and grinding bars 15.

I have found that the carbon element which forms one of the ingredients of the reactive mixture can be very advantageously supplied by using the so-called "black ash" derived 10 from soda or Kraft mills, this being a by-product obtained in such mills particularly from the waste or spent black liquor which is produced in the Kraft process of digesting wood to pulp. This is a feature of commercial advantage though any proper carbon material may be used in so far as the reactions required in this process are concerned.

This construction of apparatus serves to rapidly and effectively produce cyanide compounds and such production is made commercial by the apparatus shown and described. For instance the use of regenerator stoves illustrated in the drawings and described in the description for heating the air going to the 25 gas producer can be supplanted by a recuperator having the same effect, this being a well known construction for heating air from exhaust fuel given off by this type of apparatus. And in many other ways departure can be made from the specific and exact structure shown and described so long as it is within the terms of the claims of the invention. The actual temperature of operation, that is, the temperature maintained in 30 cylinder 1 to bring about the reaction in question, lies between 700 and 1000 degrees centigrade. The character of the carbon, as well as the character of the alkali salts used, appear to determine the actual requisite temperature. For instance a mixture of potassium 35 and sodium salts would appear to require a lower operating temperature and when either of these salts is used alone. The invention is defined in the appended claims and is to be considered comprehensive of all forms of 40 structure coming within the scope of said claims.

I claim:

1. The herein described process of alkali 45 nitrogen compound production which consists in placing reactive material in a closed receptacle, continuously and with great rapidity beating and stirring said material and maintaining it in finely divided and disseminated condition and also continuously slowly scraping the inner walls of said receptacle to

keep the walls free of said material and continuously subjecting said material to the action of highly heated reactive gases whereby alkali cyanides are rapidly produced. 60

2. The herein described process of alkali cyanide production which consists, in placing alkali forming metal salts and catalytic materials in a closed receptacle having an inlet and outlet, continually and with great rapidity stirring said salts and catalytic materials and maintaining them in finely divided and disseminated condition by means of rapidly moving metal parts which act to also beat and grind the materials, continuously 65 slowly scraping the inner walls of the reacting vessel from material deposited thereon, said scraping being accomplished by slowly moving metal parts, and continuously subjecting the materials contained in the reacting vessel 70 to the action of nitrogen gas heated above 700° centigrade, whereby alkali cyanides are produced with great rapidity.

3. The herein described process of producing sodium cyanide which consists, in placing 80 a mixture of sodium carbonate, carbon and an iron catalyst within a closed container, stirring, beating and grinding and disseminating said materials very rapidly by means of revolving metal parts rotating at high 85 speed, and also scraping the inner walls of the reaction receptacle from deposits collecting thereon by slowly moving metal scraper bars moving over the inner surface of said container, and subjecting said mixture of 90 materials to the action of highly heated nitrogen gas to thereby produce sodium cyanide.

4. The herein described process of producing sodium cyanide which consists, in placing 95 a mixture of sodium carbonate, carbon and an iron catalyst within a closed container, beating, grinding, stirring and disseminating said materials by means of rapidly moving metal parts which stir and grind the material and beat it as the material strikes against said parts thereby maintaining the same in very finely divided and disseminated condition, slowly scraping the inner walls of the reaction container to maintain it free of deposits tending to collect thereon, and continuously 100 subjecting said material to the action of nitrogen and carbon monoxide heated to a high degree of temperature in excess of 700 degrees centigrade.

In testimony whereof I affix my signature.

HERMAN B. KIPPER.
